UNITED STATES PATENT OFFICE

MAX PAUL ERNST HOHN, OF DRESDEN, GERMANY, ASSIGNOR TO THE FIRM "UNIVERSALLE" CIGARETTENMASCHINEN-FABRIK J. C. MULLER & CO., OF DRESDEN, GERMANY

CIGARETTE MACHINE

Application filed November 29, 1927, Serial No. 236,547, and in Germany September 12, 1927.

This application is a continuation in part of my co-pending application, Serial Number 141,779, filed October 15, 1926.

For the cutting up of a cigarette string into separate cigarettes the arrangement of a vibrating rotating crescent-shaped knife is known. By virtue of the vibrating or wavering movement effected in the direction of the string the knife is able to follow the movement of the string in one phase of the rotation, and penetrate into the eccentric rotation, so that neither a reciprocating movement with the string nor a reciprocating movement at right angles to the string is required for the knife pivot or its bearing. Since, however, the vibrating movement only goes with the string in a certain phase of the revolution, and since therefore the effecting of the cut is limited to the angle at the centre of the rotation circle corresponding to this phase, a particular speed of revolution of the knife is compulsory, so that the magnitude of the "pulling" movement of the knife edge in contact with the tobacco string is limited. The same limitation would be necessary if the knife were fixedly mounted as a circular knife concentrically and obliquely to the axis, and in this case the knife axis would have to effect a reciprocating movement at right angles to the direction of the string, since the knife edge itself forms a circle concentric with the axis.

According to the present invention a circular knife is itself rotatably mounted outside the axis of a pivot stationarily supported beside the string, on a vibrating or swaying carrier carried by the said pivot, and is driven round its own axis, so that it revolves in an orbit like a planet and at the same time rocks or vibrates. There is now no longer any limitation, for the effecting of the cut, to a particular phase of a complete revolution of the knife, so the path traversed during the cut by a point on the knife edge can be made as long as may be desired, so that a "pulling cut" is attained in the completest possible sense, and the blunting wear is distributed over a great length of edge and is therefore specifically reduced. A similar advantage applies with regard to the path of contact

between the knife disc and the sharpening device, so that the resharpening or whetting can be effected upon a long path of contact, with correspondingly smooth action of the elements in question on the knife edge. 55

Such a cutting device, in conjunction with the above-mentioned sharpening device, is illustrated in the accompanying drawings, wherein

Fig. 1 shows in side elevation a cutting and 60 sharpening device with a circular knife according to the invention.

Fig. 2 shows a plan thereof,

Fig. 3 shows an elevation of the grinding 65 device, and

Figs. 4, 5 and 6 show respectively an elevation, a side elevation and a plan of the knife carrier on a somewhat larger scale.

The circular knife 1 is supported with its pivot 2 in a bearing eye 3 of a carrier 4. The carrier 4 is arranged on a shaft 5 in such a manner that during its rotation it executes a swaying or oscillating movement. Upon the pivot of the circular knife is mounted a cord pulley 6, which is connected by a crossed 70 driving cord 7 with a cord pulley 9, secured to a holder 8 and arranged coaxially in relation to the shaft 5. The crossing of the driving cord is for the purpose of giving the circular knife the more correct direction of rotation and of obtaining a more favorable bearing of the driving cord on the pulleys. 75

In order to enable the carrier to be conveniently adjusted, the end of the shaft 5 projecting out of a casing 10 is constructed as a 80 fork 11. Into the fork there projects a bearing eye 12 arranged on the rear wall of the part 4' of the carrier. This bearing eye surrounds a pivot bolt 13, which is carried by the ends of the forked arm 11. Accordingly 85 the knife carrier 4, 4' can be rocked about the bolt 13. The fixing in the desired position is effected by means of positioning screws 14, which are carried by arms 15 arranged one on each side of the fork 11 and mounted on the 90 rear wall of the part 4' of the knife carrier. The ends of these screws, upon being adjusted, bear against the fork 11. Hence in this manner any desired oblique position of the knife carrier 4 can be brought about at 95

any time without difficulty, so that the circular knife 1 can be adjusted according to the velocity of the string. At the same time the angular position of the knife shaft 5 in relation to the axis of the string can be regulated in such a way that though the circular knife 1, while the cut is being effected, moves in the direction of feed of the string and with the same velocity as the string, the cut nevertheless goes through the string exactly at right angles. In order to enable the knife to be adjusted in a radial direction, slots 17 are provided for the fastening screws 16, which connect together the two parts 4 and 4' of the carrier.

A cutting tube 18 is mounted on a carrier 19, which is secured to a cross piece 20. This cross piece is carried by two rods 21, which are inserted into long guiding sleeves 22. Their ends are connected with one another by a second cross piece 23, which a connecting rod 24 connects with a crank pin 25 on a spur wheel 26.

A grinding disc 27 serves for the grinding of the circular knife 1, and since the carrier executes a vibrating movement, the cutting edge coming into contact with the grinding disc describes a curve, for which reason the grinding disc may be controlled by corresponding means.

On the knife edge the grinding disc produces a facet cut, as illustrated by Figure 6. For this reason the spindle 28 of the grinding disc must be adjusted at a corresponding inclination to the surface of the knife. The spindle of the grinding disc is supported in a bearing 29 and carries at its free end a nut 30 and a lock nut 31, for the purpose of accurately adjusting the spindle and consequently also the grinding disc 27. The bearing 29 is mounted upon a disc-shaped plate 32, which is rotatable upon a corresponding disc-shaped base plate 33 by virtue of concentric slots 34 for the connecting screws for the purpose of enabling the correct obliquity of the spindle 28 to be obtained relatively to the plane of the knife.

A carrier plate 33 is mounted at the end of a swing frame 34a, which swings about a bolt 35. This bolt is carried by a bearing eye 36, which is mounted on a slide 37. The slide is slidable in a horizontal guide 38 in a guiding piece 40 located on the part 39 of the frame. This displacement of the slide 37 is effected by means of a screw-threaded spindle 41, which extends into a screw-threaded bore in the slide, is kept engaged in a projection 42 on the guiding piece 40, and carries on its exposed end a hand wheel 43.

With the swing frame 34a there engages at 44, with the interposition of a link 46, a rod 45 guided in a straight line at 47. The other end of the rod is pivoted to a connecting rod 48, which is moved by a crank pin 49 on a spur wheel 50. Accordingly by means of the crank

and connecting rod gear 49, 48, 45, 46 and the swing frame 34a the grinding disc 27 is so controlled when moving past the obliquely positioned circular knife that it always makes contact with the cutting edge.

The grinding disc 27 has no special drive but rotates a few degrees owing to the contact of the cutting edge of the circular knife with the grinding disc slipping past it.

What I claim is:—

1. A cigarette string cutting device for cigarette machines, comprising, a knife carrier, a shaft for rotating said carrier, a circular knife mounted on said carrier, outside the axis of rotation thereof, means for causing said circular knife to rotate and means for causing said carrier to vibrate with any desired amplitude as it rotates, said last named means comprising, a forked projection formed on one end of said shaft, a pivoting bolt carried by said fork, a bearing eye arranged on said carrier and adapted to project into said fork and surround said bolt, and locking means for fixing said carrier in any desired position about said bolt, whereby the knife edge follows the forward feeding movement of the cigarette string being fed to said machine.

2. A device as per claim 1, in which said means for rotating said circular knife include a pulley coaxially secured to said circular knife, an immovable pulley mounted with its axis in the axis of rotation of the knife carrier, and an endless driving band connecting said pulleys with one another, whereby when said carrier is rotated said first pulley will also rotate.

3. A cigarette string cutting device for cigarette machines comprising a knife carrier, means for driving said knife carrier in a rotary path only, means for adjusting the angular position of said carrier relative to said driving means for causing said knife carrier to vibrate with any desired amplitude, means for fixing said carrier in said adjusted position, a circular knife adjustably supported on said carrier outside the axis of rotation of the latter, a pulley coaxially secured to said circular knife, an immovable pulley mounted with its axis in the axis of rotation of the knife carrier, and an endless driving band connecting said pulleys with one another, the motion of the carrier being such that during the cutting of a fed cigarette string by said knife the knife edge follows the forward feeding movement of the cigarette string.

4. A cigarette string cutting device for cigarette rod machines having a continuously fed cigarette string comprising a knife carrier, a driven shaft on which said carrier is mounted, means for adjusting the angular position of said carrier relative to the longitudinal axis of said driven shaft, means for fixing said carrier in said adjusted position, a circular cutter rotatably supported on said

carrier eccentrically of the axis of rotation of the latter, the relationship between said driven shaft, the carrier thereon and the direction of feed of said cigarette string being such that the cutting edge of said rotary cutter follows the feeding movement of said cigarette string when said driven shaft is rotated without displacement of said cutter in the longitudinal direction of said driven shaft and means for rotating said circular cutter about its own center.

In testimony whereof I have signed my name to this specification.

MAX PAUL ERNST HOHN.
